[57] **CLAIM**

The ornamental design for bags for motorcycles, as shown and described.

DESCRIPTION

FIG. 1 is a perspective view of one embodiment of the bags in a flat position.

1 Claim, 4 Drawing SheetsFIG. 2 is a perspective view of the embodiment of FIG. 1 showing the bags in a folded position.

FIG. 3 is a perspective view of the embodiment of FIG. 1 showing the bags in position on a motorcycle. In FIG. 3, the shape of the motorcycle shown in dashed lines forms no part of the design.

FIG. 4 is a perspective view of a second embodiment of the bags in a flat position.

FIG. 5 is a perspective view of the embodiment of FIG. 4 showing the bags in a folded position.

FIG. 6 is a perspective view of the embodiment of FIG. 4 showing the bags in position on a motorcycle. In FIG. 6, the shape of the motorcycle shown in dashed outline forms no part of the design.

FIG. 7 is a top plan view of embodiment 1, FIG. 1;

FIG. 8 is a bottom plan view thereof, with the bags separated for clarity of illustration;

FIG. 9 is a side elevational view of FIG. 8, the undisclosed side being the same;

FIG. 10 is a top plan view of FIG. 8;

FIG. 11 is a bottom plan view of FIG. 4;

FIG. 12 is a side elevational view of FIG. 4, the undisclosed side being a mirror image; and,

FIG. 13 is a top plan view of FIG. 4.

The design is intended to be used for a bag which is draped over a motorcycle.
